UNITED STATES PATENT OFFICE

136,977

DESIGN FOR A COMBINED SPONGE CUP AND SPONGE

John A. Petrullo, New York, N. Y.

Application March 30, 1943, Serial No. 109,917

Term of patent 14 years

To all whom it may concern:

Be it known that I, John A. Petrullo, a citizen of the United States, residing at New York, in the county of New York and State of New York, have invented a new, original, and ornamental Design for a Combined Sponge Cup and Sponge, of which the following is a specification, reference being made to the accompanying drawing, forming a part thereof.

In the drawing:

Figure 1 is a view in perspective of the com-

bined sponge cup and sponge embodying my new design, and

Fig. 2, a view in top plan thereof.

The characterizing features of the design comprise a sponge cup having the configuration, proportions and panelling on the sides thereof, specifically as shown.

I claim:

The ornamental design for a combined sponge cup and sponge, as shown and described.

JOHN A. PETRULLO.
